ISOMERIZATION OF PARAFFINS

Aristid V. Grosse, Bronxville, N. Y., and Herman Pines, Chicago, Ill., assignors to Universal Oil Products Company, Chicago, Ill., a corporation of Delaware

No Drawing. Application January 17, 1940,
Serial No. 314,282

4 Claims. (Cl. 260—676)

This application is a continuation-in-part of our co-pending application Serial No. 118,587, filed December 31, 1936.

This invention relates particularly to the isomerization of straight chain paraffin hydrocarbons which are normally liquid.

In a more specific sense the invention is applicable not only to individual paraffin hydrocarbons of normal straight chain structure but also to hydrocarbon mixtures containing these compounds in substantial percentages such as straight run gasolines and their fractions, which contain in addition to paraffin hydrocarbons of highly knocking characteristics other hydrocarbons comprising some paraffins of branched chain structure and the usual run of naphthalenes and aromatics. The isomerization of individual paraffin hydrocarbons such as n-pentane or n-hexane is frequently desirable in the manufacture of derivatives since the isomeric compounds are more reactive and, in the case of gasoline or gasoline fractions, the isomerization has the effect of increasing the antiknock value of the gasolines to a marked extent as will be shown in later examples.

There is no need for extensively recounting the number of possible isomers of paraffin hydrocarbons since these are all predictable on the present theories of organic chemistry and are well known to those familiar with this subject. However, the following table is shown to indicate in a general way the change in structure and properties of normal paraffin hydrocarbons and their isomers, particularly since the pentanes constitute some of the lower-boiling constituents of ordinary gasolines.

Compound	Formula	Boil- ing point	Density	Octane num- ber
n-Pentane	CH ₃ (CH ₂) ₃ CH ₃	36.3 ° C.	0.6475@0° C.	63
i-Pentane	CHCH ₂ CH ₂ CH ₃	28	0.6394@0° C.	88
Neo-pen- tane	C(CH ₃) ₄	9.5	0.6251@14.4° C.	—

It will be observed from the above that, as the structure of the molecule becomes more compact, boiling point and specific gravity both decrease while the antiknock value as expressed by octane number generally increases although figures are

not available for the neo-pentane. Similarly, the isomeric hexanes, heptanes, and octanes will show the same progressive relationships as their structure becomes more condensed. As the molecular weight of paraffin hydrocarbons increases, the number of possible and known isomers increases more than arithmetically so that in case of isomerization involving mixtures of n-paraffins and particularly n-paraffins in admixture with other hydrocarbons in gasolines, the determination of the extent of isomerization is not possible by analytical methods but can be estimated from the observed change in antiknock value.

In one specific embodiment the present invention comprises treatment of n-paraffin hydrocarbons or hydrocarbon mixtures containing substantial percentages thereof such as straight run gasoline fractions with catalysts comprising zirconium chloride and hydrogen chloride to effect isomerization reactions.

Zirconium chloride is a white crystalline solid which sublimes at 300° C. and has been found to be effective in promoting isomerization of normally liquid normal paraffin hydrocarbons into substantial percentages of isomeric compounds of more highly branched structure and also of increased degree of branching in hydrocarbons which may have some side chains but not the maximum possible number. It has further been found that this isomerization which is of particular benefit in the treatment of straight run gasolines to improve their antiknock value is best conducted in the presence of small but necessary proportions of hydrogen chloride. The temperature, pressure, and times of contact necessary for effecting an optimum amount of isomerization will obviously vary with each compound or mixture of compounds treated so that only broad ranges of these factors can be given. In general, temperatures of 0°—300° C., normal atmospheric or moderately superatmospheric pressures and varying times of contact may be employed depending upon whether the operations are conducted in batch or continuous types of plants. In any case there will be an optimum set of conditions at which maximum isomerization reactions are effected with minimum decompositions involving the breaking of carbon-to-carbon bonds and the formation of hydrocarbons of lower and higher molecular weight than the original material treated.

The present process may be operated under batch or continuous conditions and either in liquid, mixed or vapor-phase as may be desirable or expedient in view of the particular hydrocarbon or hydrocarbon mixture undergoing treatment. A

simple method of operation consists in adding 5 to 10 per cent of granular anhydrous zirconium chloride to a treating vessel containing hydrocarbons and provided with a mechanical agitating device of some description. It is best to employ a treater which can be sealed from atmospheric contact and which can be operated under superatmospheric pressure. The solid catalyst is then kept in suspension by moderate agitation while introducing a slow stream of hydrogen chloride.

In another type of operation which accelerates the rate of isomerization, the hydrocarbon mixture may be kept at its boiling point by moderate heating under reflux conditions with the granular chloride maintained in suspension by the ebullition, while the hydrogen halide is again added in a slow stream. In this type of operation any desired superatmospheric pressure may be employed to permit the use of any desired temperature. The necessary amount of hydrogen chloride may be generated by adding a small amount of water or steam which causes an equivalent amount of hydrolysis. Vapor-phase operations may be conducted by passing vapors of hydrocarbons mixed with a small amount of hydrogen chloride over solid granular catalysts comprising the zirconium chloride. The compound may also be vaporized in a stream of inert gas and injected into a slow stream of the vapors of a hydrocarbon undergoing isomerization after which the spent or partly spent catalyst may be settled and the products fractionated.

The following example is introduced for the purpose of illustrating the type of results normally obtainable by the use of the process of the invention although not with the intention of unduly restricting its proper scope.

Normal pentane was placed in a pressure vessel and approximately 30% by weight of powdered and substantially anhydrous zirconium chloride

was added. The pressure vessel was closed and an amount of hydrogen chloride introduced which corresponded to approximately 4% by weight of the normal pentane. The pressure vessel was then heated for three hours at approximately 150° C. and the products removed from the pressure vessel were then found to have the following composition:

	Per cent
Propane	20 10
Iso-butane	41
n-Butane	19
i-Pentane	14
n-Pentane	3
Higher hydrocarbons	3 15

We claim as our invention:

1. A process for the isomerization of straight chain paraffin hydrocarbons which comprises subjecting said hydrocarbons to the action of zirconium chloride and hydrogen chloride. 20
2. A process for the isomerization of normally liquid straight chain paraffin hydrocarbons which comprises subjecting said hydrocarbons to the action of zirconium chloride and hydrogen chlo- 25 ride.
3. A process for the isomerization of normally liquid hydrocarbon mixtures containing substantial percentages of straight chain paraffin hydrocarbons which comprises subjecting said hydrocarbon mixtures to the action of zirconium chlo- 30 ride and hydrogen chloride.
4. A process for the isomerization of gasoline fractions containing substantial percentages of straight chain paraffin hydrocarbons which comprises subjecting said fractions to the action of zirconium chloride and hydrogen chloride. 35
